CLAIM

The ornamental design for a condiment grinder with flip-top lid, as shown and described.

DESCRIPTION

FIG. 1 is a front left perspective view illustrating our design for a condiment grinder with flip-top lid.

FIG. 2 is a front view thereof.

FIG. 3 is a left side view thereof.

FIG. 4 is a rear view thereof.

FIG. 5 is a right side view thereof.

FIG. 6 is another right side view thereof, with the flip-top lid in an open position.

FIG. 7 is a bottom view thereof.

FIG. 8 is a top view thereof; and,

FIG. 9 is another top view thereof, with the flip-top lid in the open position.

The broken lines in the drawings illustrate portions of the article that form no part of the claimed design. The stippling used in the drawings is to indicate portions of the article that are translucent.
